DISPLAY PACKAGE FOR TOOTHBRUSH OR SIMILAR ARTICLE

George R. Stehl, Stony Brook, N.Y., assignor to Warner-Lambert Pharmaceutical Company, Morris Plains, N.J., a corporation of Delaware

Filed Sept. 16, 1966, Ser. No. 3,892

Term of patent 14 years

(Cl. D9—239)

FIG. 1 is a perspective view of a display package for toothbrush or similar article showing my new design;

FIG. 2 is an exploded perspective view thereof;

FIG. 3 is an enlarged cross-sectional view taken on line 3—3 of FIG. 1.

I claim:

The ornamental design for a display package for toothbrush or similar article, substantially as shown.
